United States Patent Office

Des. 203,999
Patented Mar. 8, 1966

203,999

DOLL

Ilse Von Schenk, Essex Junction, Vt., assignor to The Western Union Telegraph Company, New York, N.Y., a corporation of New York

Filed June 5, 1964, Ser. No. 80,297

Term of patent 14 years

(Cl. D34—4)

FIG. 1

FIG. 2

FIGURE 1 is a front view of a doll showing my design; FIGURE 2 is a side view thereof; and

FIG. 3 is a fragmentary front perspective view. The back of the doll is plain and unornamented.

I claim:

The ornamental design for a doll, substantially as shown and described.
